UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,943, dated November 1, 1892.

Application filed October 3, 1892. Serial No. 447,728. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of a series of ornaments of the German renaissance style, as represented in the accompanying drawing. Each ornament is composed of connected scrolls forming a lyre-shaped ornament with branches springing from the base and extending upwardly on either side and bearing flowers. The ornaments are arranged at regular intervals over the surface of the paper and are printed in any color or colors or in bronze upon tinted paper of any desired 20 color.

What I claim is—

The design for wall-paper herein shown and described.

Witness my hand this 30th day of September, 1892.

CHARLES BOOZE.
